UNITED STATES PATENT OFFICE.

FRIEDRICH A. GUSTAV PIRWITZ, OF ROCHESTER, NEW YORK.

PHOTOGRAPHIC CAMERA.

1,317,034.

Specification of Letters Patent. Patented Sept. 23, 1919.

Application filed May 14, 1917. Serial No. 168,574.

To all whom it may concern:

Be it known that I, FRIEDRICH A. GUSTAV PIRWITZ, a citizen of the United States, and resident of Rochester, in the county of Monroe and State of New York, have invented 5 certain new and useful Improvements in Photographic Cameras, of which the following is a specification.

The present invention relates to photographic cameras, and more particularly to 10 the type which employs a sensitized material in the form of a film movable from one roller to another to expose successive portions thereof.

15 An object of this invention is to provide an improved film winding mechanism of the type in which a compensating means is employed for determining the length of the successive movements of the film winding 20 means, said compensating means embodying a plurality of stops with a selector controlled by the film winding means. Another feature of the invention is a connection between the operator and the film winding key which 25 will permit the turning of the film winding key independently of the operator.

Still another object of the invention is to provide a construction for carrying out the hereinbefore mentioned objects which will be 30 simple and accurate in its operations, not likely to get out of order, and inexpensive to manufacture.

To these and other ends, the invention consists of certain parts and combinations 35 of parts, all of which will be hereinafter described, the novel features being pointed out in the appended claims.

In the drawings:—

Figure 1 is an enlarged vertical section 40 through the operator and its connection with the film spool;

Fig. 2 is a detail view of the invention showing the operator shifted and about to move the selector;

45 Fig. 3 is an enlarged section on the line 8—8, Fig. 2;

Fig. 4 is a detail side view; and

Fig. 5 is a detail view showing the manner 50 in which the selector is finally moved by the film winding lever.

This embodiment of the invention employs a film winding mechanism in which the film is moved from one roller 7 on to the other by a single operating member, the mounting 55 of said member being controlled by a compensating means.

In the illustrated embodiment of the invention, the spool 7 is held at one end by a key 8 arranged on the stub shaft 9 which is journaled in the casing 1 and is 60 adapted for axial movement. This key is moved toward the spool 7 by a helical spring 10 which, in turn, is inclosed within a tube 11, having its opposite walls slotted at 12 to form guides for the key 8. A clutch may be 65 interposed between the sleeve or tube 11 and the sleeve 11^b on the casing, for the purpose of preventing the return movement of the spool so as to keep the film taut. This clutch may be of any suitable construction as for 70 instance an ordinary roller clutch having rollers 11^a adapted to produce a binding action between the sleeves 11 and 11^b. It is apparent that, if the shaft 9 be turned, the spool 7 will also turn, and if the shaft 9 be 75 moved axially to withdraw the key 8 from engagement with the spool 7, the latter may be removed. A thumb piece 13 is arranged on the outer end of the shaft 9 to facilitate the manipulation of the shaft 9. On the 80 shaft 9 a pinion 14 is arranged, and this pinion is engaged by a gear 15 which is journaled on a stub shaft 16 mounted on the casing 1 to one side of the shaft 9. Also turning on the stub shaft 16 is an operating 85 member or lever 17, the latter having a clutch connection with the gear wheel 15, whereby, when the operating member is moved in one direction, motion will be transmitted to the gear wheel 15, and, when the 90 operating member is moved in the other direction, the gear wheel 15 will remain stationary. At the same time, this clutch connection permits the rotation of the film by means of the thumb piece 13, independently 95 of the operating member 17, to permit the film to be shifted independently of the other portions of the winding mechanism. Any suitable clutch connection may be employed between the operator 17 and the gear 15, 100 that shown embodying an annular depending flange 18 on the operating member 17, having its inner periphery adapted to be engaged by cylindrical rollers 19, which are pressed outwardly by cam projections on the gear wheel 15 to engage the flange 18 when the operating member is turned in one direction, but which recede or move away from the flange when the operating member 17 is moved in the other direction, this being a 105 common form of clutch.

The movement of the operating member

or lever 17 is such that one swing thereof, in one direction, will shift the film a distance sufficient to wind the exposed portion thereof on one of the spools 7, while at the same time presenting another portion of the film for exposure. It is apparent that the movement of this lever must be changed or shortened with each exposed portion wound on the roller 7, for the diameter of the roller 10 and the film gradually increases. This is effected automatically by a compensating means which embodies, in this instance, a stop 32, which is yieldingly mounted on the lever 17, and is adapted to coöperate successively with the stationary stops 33 which are arranged concentrically about the pivot of the film winding lever 17. These stationary stops 33 are beveled on one and the same side at 34, so that, when the operating lever 20 17 is moved in one direction, the stop 37 will coöperate with said beveled faces and ride over the stops, but when the lever 17 is moved in the other direction, if nothing interferes with the action, the stop 32 will coöperate with the stops 33 to limit the movement of the operating lever. In order to determine which of the stops is to be engaged, a selector is employed which causes the stop 32 to successively engage the stops 33 to shorten the throw of the operating lever 17 on each successive movement. This selector, in this instance, embodies a shifting member having two curved arms 35 and 36 connected together at one of their ends 30 and separated at their other ends, these arms lying on opposite sides of the curved series of stops 33. The top surface of one of these arms is in a plane slightly above the uppermost end of the stops 33, so that when said surface lies adjacent to said stops, it will 40 serve as a guide for the stop 32 and prevent engagement between said stop 32 and the stops 33. The other arm 35 of the selector yields laterally and is bent or deflected inwardly at 37, so as to project between the stops 33 in order to hold the selector in its shifted position.

It is apparent that the selecting device can be moved in a line which will cause it to successively expose the stops 33 for engagement by the stop 32. This movement of the selecting device is preferably step-by-step, and is accomplished by providing a shoulder 38 on the selecting device at the end of the guide arm 36. When the stop 32 reaches the end of the guide arm 36, it drops behind the shoulder 38, so that, upon the return movement of the stop 32, the selecting device will be shifted until the stop 32 engages the beveled face 34, after which said stop 32 will pass onto the guide portion 36. Upon the stop 32 reaching the first portion of the guide, a portion or shoulder 39 on the film shifting lever 17 60 will coöperate with the extreme end of the

arm 35, due to the deflection of said arm into the path of said portion 39 by the engagement of the portion 37 with one of the stops 33, as will be more clearly shown in detail in Fig. 10. A slight shifting of the selector causes said portion 37 to ride off such stop 33 and enter between said stop 33 and the adjacent stop 33, thus carrying the end 40 out of the path of the portion 39, so that the film-operating member 17 may return to its original position without shifting the selector. Upon the movement of the operating member 17 to wind the film again, the stop portion 32 rides upon the beveled end 41 of the selector and travels on the 80 guide arm 36 until the shoulder 38 on said guide arm 36 is reached, when the stop 32 lowers and engages with that stop 33 which is closest to the shoulder 37, thus limiting the movement of the film winding lever 17. 85 To guide the selector in a path concentric with the axis of turning of the film-winding lever 17, the selector is provided with a projection 42 depending into a guide groove 43 formed in a plate on the camera casing 90 1. After the selector has been shifted to the end of its movement, due to the winding of the film, said selector is returned so that the end thereof exposes the first stop 33 for engagement by the stop 32, this return being effected by pressing with the fingers upon the selector at the end thereof, forming a connection between the arms 35 and 36. It is apparent, however, that the selector may be returned to its original position by any other suitable means. An index or pointer 35^a may be provided on the selector to coöperate with a scale 35^b on the casing so as to point out the number of the exposure. 95

With a camera constructed in accordance with this invention it is possible to employ a film winding mechanism in which the operator has a single movement to shift the film the desired distance and is controlled by a 110 compensating means which employs a plurality of fixed stops under the control of a selector which successively exposes said stops for engagement by the film winding mechanism. 105

What I claim as my invention and desire to secure by Letters Patent is:—

1. In combination in a film camera, an axially movable film winding key having a finger piece thereon and also a pinion on its 120 shaft, a gear wheel meshing with said pinion and arranged so that the latter may be moved out of mesh therewith to turn the key independently of the gear, and an operator connected to the gear to turn the latter. 125
2. In combination in a camera having a film winding means, compensating means for determining the lengths of the successive movements of the film winding means comprising a plurality of stationary stops, and 130

a movable selecting means controlled by said film winding means and coöperating with said stops to determine the effective one.

having a film winding means, a yieldingly mounted stop on the film winding means, a plurality of stationary stops for successively engaging said yieldingly mounted stop, and 25 means for holding said yieldingly mounted stop out of coöperation with those stationary stops over which the yieldingly mounted stop must pass to coöperate with the desired stationary stop.

30

6. In combination in a roll film camera having a film winding means, a yieldingly mounted stop on the film winding means, a plurality of stationary stops for successively engaging said yieldingly mounted stop, and 35 a shiftable guide for holding the yieldingly mounted stop out of engagement with those stationary stops over which the yieldingly mounted stop must pass to coöperate with the desired stationary stop.

3. In combination with a roll film camera having a film winding means, provided with an operator having a stop, a plurality of stationary stops for coöperating with the stop on the operator, and selecting means controlled by said film winding means for 10 causing said operator stop to successively engage said stationary stops to determine movements in the operator corresponding to the amount of material on the film roll of the camera.
- 15 4. In combination in a roll film camera having a film winding means provided with an operator having a stop, a plurality of stationary stops, and a selector for the stationary stops controlled by the film winding means.
- 20 5. In combination in a roll film camera
